UNITED STATES PATENT OFFICE

EDWARD E. HILER, OF BLOOMFIELD, NEW JERSEY

MULTISTAGE AUDIO AMPLIFICATION SYSTEM

Application filed August 21, 1929. Serial No. 387,318.

This invention relates, generally, to electron discharge device amplification systems; and the invention has reference, more particularly, to multi-stage push-pull audio frequency amplifier circuits.

Heretofore, use has been made of transformer coupled push-pull audio amplification, wherein the secondary winding of the input transformer is center tapped to the filament or ground portion of the circuit and the other terminals of this winding are connected to the grids of the oppositely arranged electron discharge devices. This arrangement eliminates the effect of the second harmonics generated in the electron discharge devices, for in operation at any given instant the voltage impressed on the grid of one device is increasing while that impressed on the grid of the other device is decreasing. Thus the grid or input circuits of the devices are 180 degrees out of phase causing the fundamental currents in the two plate circuits to differ by 180 degrees. A center tapped coil may be used in the output circuit of the electron discharge devices in lieu of an output transformer, in which case the center tap of the coil is connected to the positive terminal of a "B" battery, and the other terminals are connected to the plates of the two devices.

When employing the center tapped coil, the fundamental signal in passing from the plate of one device or tube through the output coil to the center tap is 180 degrees out of phase with the fundamental signal passing from the plate of the other device to the said center tap. However, owing to the push-pull arrangement, the fundamental currents passing from the plates of the devices through the sections of the coil are in phase, causing their magnetic fields to be additive, as desired, while the harmonics are balanced out.

The use of audio transformers in the input circuits of such amplification systems, however, results in distortion due to the impossibility of obtaining one hundred percent coupling between the primary winding and the tapped secondary winding of the transformer. Furthermore, in using input trans-

sary in order to obtain satisfactory operation to employ resistances in shunt with the secondaries of the transformers, which resistances have the effect of reducing the undesirable effects of resonance peaks, the use of which resistances, however, not only complicates the circuit but adds to the cost thereof. When more than one stage of transformer coupled push-pull audio amplification is employed, the distortion increases.

In my copending application Serial No. 378,058, filed July 13, 1929, there is disclosed a novel form of single stage push-pull audio frequency amplifier circuit which eliminates the objections and undesirable features present in the use of transformer coupled push-pull audio amplifiers.

The principal object of the present invention is to provide a novel multi-stage push-pull audio frequency amplifier circuit employing double impedance coupling in lieu of transformer coupling.

The use of the novel double impedance coupling of this invention not only produces substantially distortionless amplification but has other decided advantages over transformer coupling. One of these advantages lies in the elimination of shunt resistances, since capacity coupling is employed instead of magnetic coupling, which design eliminates the resonant peaks at the high frequencies. On account of not having a cut off at the high frequencies, the range of frequencies made possible by using double impedance coupling can be extended to cover the wide band of frequencies necessary for reproduction in high quality music and television applications.

By utilizing the method outlined in my prior Patent No. 1,715,501, the low audio frequencies below 150 cycles can be exaggerated, if desired, to compensate for the usually poor response of loud speakers to low frequencies.

Other objects of this invention not at this time more particularly enumerated will be clearly understood from the following detailed description of the same.

The invention is clearly illustrated in the accompanying drawing, the single figure of

which is a wiring diagram of a multi-stage push-pull audio frequency amplification system embodying the principles of this invention.

5 Referring now to the said figure, the reference character 1 designates an electron discharge device or tube which may be employed as a detector or as an audio amplification tube. The grid 2 and filament heated 10 cathode 3 of the tube 1 may be connected to any suitable input circuit, the output of which it is desired to amplify. The heating filament 4 of tube 1 may be heated by alternating current supplied by a generator 5, the 15 said generator being coupled in any suitable manner to the filament 4, as by a transformer 6. A resistance 7 is connected across the terminals of the secondary winding of transformer 6, and the mid-point of resistance 7 20 is connected to the lead of cathode 3 which lead is illustrated as grounded at 8. This arrangement causes the potential of the cathode 3 to be the same as the average potential of the heating filament 4. The plate 25 or anode 10 of this tube is illustrated as connected through a plate choke coil 11 to a terminal post 12 adapted to be connected to a "B" eliminator terminal. Inasmuch as any suitable "B" eliminator may be employed for 30 this purpose and as the same forms no part of the present invention it is not shown in the drawing.

The plate 10 of tube 1 is connected through a coupling condenser 14 to the grid of a tube 35 15 arranged in opposition or push-pull relation with a similar tube 16. Generator 5 is illustrated as supplying heating current to the cathode heating filaments of tubes 15 and 16. The external cathode-grid circuit of tube 40 15 extends through a resistance 18 and the upper half of a center tapped grid choke coil 19. The resistance 18 serves to cause the desired negative bias to be placed upon the grid of tubes 15 and 16. A condenser 17 45 is connected across the resistance 18 for bypassing alternating currents. The center tap of choke coil 19 is grounded at 20. The external filament-grid circuit of tube 16 extends through resistance 18 and the lower 50 half of grid choke coil 19. The upper half of grid choke coil 19 serves not only as a grid choke for tube 15 but also as the primary of a one to one transformer, the secondary of 55 which is the lower half of choke coil 19. Grid choke coil 19 therefore serves to cause the potentials impressed on the grids of tubes 15 and 16 to be substantially 180 degrees out of phase so that the fundamental plate circuit currents of these tubes also differ in 60 phase by 180 degrees while the harmonics generated will be in phase.

The plates or anodes of tubes 15 and 16 are connected to the outer terminals of a center tapped plate choke coil 22. The center 65 of choke coil 22 is connected to a terminal

post 21 adapted to be connected in turn to a suitable "B" eliminator terminal. Owing to the push-pull arrangement of tubes 15 and 16, though the fundamental currents in the plate circuits of these tubes differ by 180 degrees, yet the magnetic fields set up by these currents in the choke coil 22 are additive while those set up by the harmonics are opposed and offset each other. 70

The plate of tube 15 is connected through a coupling condenser 23 to the grid of a tube 24 arranged in opposition or push-pull relation with a similar tube 25. The plate of tube 16 is connected through a coupling condenser 26 to the grid of tube 25. A center tapped grid choke coil 27 is connected between the grid input circuits of tubes 24 and 25 and has its center tap grounded at 29. The external cathode-grid circuit of tube 24 extends through a resistance 28 and the upper 85 half of grid choke coil 27, whereas the external cathode-grid circuit of tube 25 extends through resistance 28 and the lower half of grid choke coil 27. A condenser 30 is connected across resistance 28. The cathode heating filaments of tubes 24 and 25 are also shown as supplied with heating current from the generator 5. 90

The plates or anodes of tubes 24 and 25 are connected to the outer terminals of a center tapped plate choke coil 31. The center tap of choke coil 31 is connected to the terminal post 32 provided for connection to a "B" eliminator. Owing to the push-pull arrangement of tubes 24 and 25, though the fundamental currents in the plate circuits of these tubes differ by 180 degrees, yet the magnetic fields set up by these currents in the choke coil 31 are additive while those set up by the harmonics are opposed and offset each other. 95 100

The plate or anode of tube 24 is connected through a coupling condenser 34 to the grid of a three electrode tube 35 arranged in opposition or push-pull relation with a similar tube 36. The plate of tube 25 is connected through a coupling condenser 37 to the grid of tube 36. A center tapped grid choke coil 38 is connected between the grid input circuits of tubes 35 and 36 and has its center 110 115 tap grounded at 39.

The electron discharge devices 35 and 36 are illustrated as having filamentary cathodes which are shown as heated by alternating current supplied by a generator 41 through a transformer 42. A resistance 43 is connected across the terminals of the secondary winding of transformer 42, and the mid-point of resistance 43 is connected through a grid biasing resistance 44 to ground 45. A condenser 46 is connected across resistance 44 for bypassing alternating currents. 120 125

The external filament-grid circuit of the tube 35 extends through resistance 44, 130

grounds 45 and 39 and the upper half of grid choke coil 38, whereas the external filament-grid circuit of tube 36 extends through resistance 44, grounds 45 and 39 and the 6 lower half of grid choke coil 38.

The plates or anodes of tubes 35 and 36 are connected to the outer terminals of a center tapped output choke coil 47. The center tap of choke coil 47 is illustrated as connected to a terminal post 48 provided for connection to a "B" eliminator. A loud speaker or telephone 49 is illustrated as connected in shunt across the terminals of choke coil 47.

In operation, the output of tube 1 impresses 15 an alternating current potential across choke coil 11. Since condenser 14 and choke coil 19 are connected in shunt with choke coil 11 through the "B" eliminator, an alternating current potential of substantially the same 20 value as impressed across coil 11 is impressed upon choke coil 19 since there is but little drop in potential across condenser 14. An alternating current potential is therefore applied to the grid of electron discharge device 15. Since the lower half of coil 19 is 25 magnetically coupled to the upper half thereof, an alternating current potential is impressed on the grid of tube 16 which potential, however, increases simultaneously with 30 a decrease in potential impressed on the grid of tube 15.

Assuming at any instant that the grid potential of tube 15 causes the fundamental plate A. C. of this tube to flow from the 35 center tap of coil 22 in a direction toward the plate of tube 15, then there will be caused by the grid potential of tube 16 a plate current flowing in a direction from the plate of tube 16 toward the center tap of coil 22, so that these currents are additive in these 40 coils. As is well known to those skilled in the art, the voltages impressed on the grids of these tubes generate harmonics which are in phase and which therefor balance out in 45 the plate circuits.

Since condenser 23 and the upper half of choke coil 27 are connected in shunt with the upper half of choke coil 22 through the "B" eliminator, an alternating current potential 50 of substantially the same value as impressed across the upper half of coil 22 is impressed upon the upper half of coil 27 since there is but little drop in potential across condenser 23. An alternative current potential 55 is therefore applied to the grid of electron discharge device 24. Also, since condenser 26 and the lower half of choke coil 27 are connected in shunt with the lower half of coil 22 through the "B" eliminator, an alternating current potential of substantially the 60 same value as impressed across the lower half of coil 22 is impressed upon the lower half of coil 27 causing an alternating current potential to be applied to the grid of electron 65 discharge device 25.

Since the A. C. potential in the plate circuits of devices 15 and 16 are substantially 180 degrees out of phase the potentials impressed on the grids of devices 24 and 25 will also be substantially 180 degrees out of 70 phase causing the plate currents of these tubes to be likewise out of phase but nevertheless additive in their magnetic effect in the choke coil 31.

The fundamental signals delivered by 75 tubes 15 and 16 and as amplified by tubes 24 and 25 is delivered to tubes 35 and 36 for further amplification. Obviously as many stages of audio amplification as desired may be employed for amplifying the fundamental signals. The output currents of tubes 35 and 36 are likewise additive in the output 80 choke coil 47 while harmonics are cancelled out.

Since extraneous "B" eliminator A. C. voltages, which would tend to produce a hum at 85 the speaker 49, are delivered to the center taps of coils 22, 31 and 47 and divide flowing in opposite directions through these coils, the magnetic fields of these currents in the 90 halves of the coils are opposed and balance out, thereby eliminating hum and iron core saturation. Owing to the fact that the novel double impedance amplifier of this invention serves to amplify the lower frequencies better than transformers, the canceling out of the extraneous A. C. voltages delivered by the 95 "B" eliminator to the center taps of the plate choke coils is an important feature of the present invention.

Although the electrodes of the thermionic 100 devices are illustrated as supplied with energy from alternating current sources, it is to be understood that direct current supply may be used if desired.

As many changes could be made in the above construction and many apparently widely different embodiments of this invention could be made without departing 105 from the scope thereof, it is intended that all matter contained in the above description or shown in the accompanying drawing shall be interpreted as illustrative and not in a limiting sense.

I claim:—

1. In an audio frequency amplifier circuit, the combination with a pair of electron discharge devices, each of said devices having a grid element together with a cathode and anode, of external circuits extending between the cathode and grid elements of said devices, transformer means having two magnetically coupled windings solidly connected in series, said transformer means having the first of its windings connected in the external circuit of one of said devices and the second of its windings connected in the external circuit of the other of said devices, and a pair of coupling circuits, the first of said coupling circuits being connected to the first winding of 110
- 120
- 125
- 130

said transformer means, and the second of said coupling circuits being connected to the second winding of said transformer means, whereby current flowing in said first coupling circuit through said first winding acts to supplement the voltage in said second winding, and current flowing in said second coupling circuit through said second winding acts to supplement the voltage in said first winding, said first and second windings serving, respectively, as grid chokes for the respective electron discharge devices.

2. In an audio frequency amplifier circuit, the combination with a pair of electron discharge devices, each of said devices having a grid element together with a cathode and anode, of external circuits extending between the cathode and grid elements of said devices, transformer means having two magnetically coupled windings solidly connected in series, said transformer means having the first of its windings connected in the external circuit of one of said devices and the second of its windings connected in the external circuit of the other of said devices, and a pair of coupling circuits, each of said coupling circuits having a condenser therein, the first of said coupling circuits being connected to the first winding of said transformer means, and the second of said coupling circuits being connected to the second winding of said transformer means, whereby one of said condensers and the first winding of said transformer means are arranged in series in said first coupling circuit and the other of said condensers and the second winding of said transformer means are arranged in series in said second coupling circuit.

3. In a audio amplifier circuit, in combination, a pair of electron discharge devices arranged in opposition and adapted to be connected to signal circuits, each of said devices having a grid element together with a cathode and anode, external circuits extending between the cathode and grid elements of said devices, a center tapped transformer means having portions thereof respectively included in said respective circuits, the ends of said transformer means being respectively connected to the respective grid elements of said devices and its tapped center being connected to the cathodes of said devices, the respective portions of said transformer means serving as grid chokes for the respective discharge devices, a second pair of similar electron discharge devices having external circuits extending between the cathode and grid elements of said devices, and a pair of condensers, each of said condensers serving to couple the external circuit of a respective one of said second pair of electron discharge devices to the anode of a respective one of said first pair of electron discharge devices.

4. In a push-pull double impedance coupling circuit for audio amplification, in com-

bination, a pair of thermionic tubes arranged in opposition and having cathode and grid elements, a pair of coupling condensers, each of said condensers, respectively, serving to couple a respective one of the cathode grid circuits of said tubes to a respective input circuit, transformer means having two magnetically coupled windings solidly connected in series, said transformer means having the first of its windings connected in the external circuit of one of said tubes and the second of its windings connected in the external circuit of the other of said tubes, whereby current flowing in one of the input circuits through one of said condensers and said first winding, acts to supplement the voltage in said second winding, and current flowing in the other input circuit through the other of said condensers and said second winding acts to supplement the voltage in said first winding.

In testimony, that I claim the invention set forth above I have hereunto set my hand this 15th day of August, 1929.
